(57) **CLAIM**

The ornamental design for a blade, as shown and described.

DESCRIPTION

FIG. 1 is a left perspective view of a blade embodying the new design;

FIG. 2 is a right side elevation view of the blade;

FIG. 3 is a left side elevation view of the blade;

FIG. 4 is a top plan view of the blade;

FIG. 5 is a bottom plan view of the blade;

FIG. 6 is a front side elevation view of the blade; and,

FIG. 7 is a rear side elevation view of the blade.

The broken line depicts portions of the blade in which the design is embodied that are not considered part of the claimed design.
